UNITED STATES PATENT OFFICE.

JOHN P. FINEGAN, OF MILBANK, SOUTH DAKOTA.

WATERING DEVICE.

SPECIFICATION forming part of Letters Patent No. 781,645, dated February 7, 1905.

Application filed July 2, 1904. Serial No. 215,047.

To all whom it may concern:

Be it known that I, JOHN P. FINEGAN, a citizen of the United States, residing at Milbank, in the county of Grant and State of South Dakota, have invented certain new and useful Improvements in Watering Devices; and I do hereby declare the following to be a full, clear, and exact description of the invention, such as will enable others skilled in the art to which it appertains to make and use the same.

My invention has for its object to provide an improved watering-trough for chickens and other fowls; and to this end it consists of the novel devices and combinations of devices hereinafter described, and defined in the claims.

The invention is illustrated in the accompanying drawings, wherein like characters indicate like parts throughout the several views. Figure 1 is a view in side elevation, showing the improved watering-trough. Fig. 2 is an end elevation of the trough, and Fig. 3 is a vertical section on the line x^3x^3 of Fig. 2.

The body of the device is afforded by a cylindrical drum 1, which is horizontally disposed and at one end is provided with a projecting cylindrical flange 2. Extending transversely of the drum, at the lower portion thereof and at the outer edge of its projecting flange 2, is a segmental web or plate 3, the upper edge of which is horizontal. The head 1^a of the drum 1 is cut away at 4 to afford a water-outlet passage of approximately the form of the web 3, but the upper edge of which

stands in a considerably lower plane. This opening 4 may, however, take various forms. The web 3 co-operates with the lower portion of the flange 2 and drum-head 1^a to form a trough out of which the fowls may drink.

The drum 1 is supported in its horizontal position by means of legs 6, directly and rigidly secured to metallic hoops 7, which hoops are clamped around said drum by means of short nutted bolts 8, passed through perforated outturned ends 9 thereof. This manner of applying the legs to the drum permits the legs to be adjusted to irregularities in the ground and permits the upper edge of the trough 5 to be set in a horizontal position even when the legs are rested upon a side hill

or upon an inclined support. Furthermore, the legs are made readily detachable for the purpose of shipment.

The trough 5 is covered by a skeleton guard plate or grating 10, which is hinged at its upper edge, as shown at 11, to the outer central portion of the head 1^a. This grating normally stands in a downwardly-inclined position, with its free edge resting on the upper edge of the web 3; but it is adapted to be turned upward into the position indicated by dotted lines in Fig. 3, so as to afford unobstructed access to the trough 5 for the purpose of cleaning it. It will be noted that the ends of the grating 10 are segmental, so that it is adapted to fit within the cylindrical flange 2 in both positions. The openings in the grating 10 are of such size that large chickens or other fowls may pass their heads therethrough into the water contained within the trough, but are not large enough to permit very small or young chickens to fall through the grating and into the trough. This watering-trough is especially intended for use where a large trough is desired and in which, on account of the size of the trough, small chickens would be very liable to get drowned were not a suitable protector or guarding device provided. The protector or guard described, while efficient for the purposes had in view, is of very small cost and may be quickly turned out of the way to give unobstructed access to the trough.

To fill the reservoir or body of the tank with water, it is necessary to turn the same into a vertical position, with its flanged end 2 upward, and it may then be filled by pouring water into the basin-like receptacle afforded by the said flange 2. When the tank is filled and turned down into a horizontal position, the water will run through the opening 4 into the trough 5 and nearly, but not quite, fill the same; but atmospheric pressure will of course prevent the water from overflowing the trough 5. When, however, the water in the trough 5 is lowered approximately down to the upper portion of the passage 4, air will be permitted to enter the tank and water will flow again into the trough 5. As soon as the water in the trough 5 rises slightly above the upper

extremity of the passage 4 it again cuts off the flow of air into the tank and stops the flow of water therefrom into the said trough. In this way the water in the trough is automatically maintained at substantially a constant height.

The device described is extremely simple and of small cost and in actual practice has been found efficient for the purposes had in view.

What I claim, and desire to secure by Letters Patent of the United States, is as follows:

1. The combination with the tank 1 having the flange 2 and the head 1^a formed at its lower portion with the water-passage 4, of the web 3 secured to said flange 2, and coöperating therewith, and with said head 1^a, to form a trough, and the guard-grating 10 hinged to said head 1^a at 11 on a line horizontally inter-

secting the axis of the tank and having its ends 20 to conform to the projecting flange 2, and normally resting in an inclined position, with its lower edge engaging the upper edge of said web 3, substantially as described.

2. The combination with a cylindrical tank 25 1, formed at one end with a trough 5 receiving water therefrom, of the hoops 7 having the legs 6 directly secured thereto and being broken at one point so as to have ends, said hoops being clamped around said drum by 30 bolts applied to the ends thereof, substantially as described.

In testimony whereof I affix my signature in presence of two witnesses.

JOHN P. FINEGAN.
